(57) **CLAIM**

The ornamental design for a carrying case for the portable external defibrillator, as shown and described.

DESCRIPTION

FIG. 1 is a perspective view of the carrying case for a portable external defibrillator;

FIG. 2 is a front view thereof;

FIG. 3 is a side view thereof;

FIG. 4 is an opposite side view thereof;

FIG. 5 is a top plan view thereof;

FIG. 6 is a bottom plan view thereof;

FIG. 7 is a rear view thereof;

FIG. 8 is a front view, shown in the open position;

FIG. 9 is a perspective view of a second embodiment of the carrying case for a portable external defibrillator;

FIG. 10 is a front view thereof;

FIG. 11 is a side view thereof;

FIG. 12 is an opposite side view thereof;

FIG. 13 is a top plan view thereof;

FIG. 14 is a bottom plan view thereof;

FIG. 15 is a rear view thereof; and,

FIG. 16 is a front view, shown in the open position.

The broken lines presented in the figures is for illustrative purposes only and forms no part of the claimed ornamental design as shown and described herein.
